US0D1068639S

(12) **United States Design Patent** (10) **Patent No.:** **US D1,068,639 S**
(45) **Date of Patent:** **** Apr. 1, 2025**

(54) **BATTERY**

(71) Applicant: **Nikon Corporation**, Tokyo (JP)

(72) Inventors: **Yasuhiko Kon**, Kawasaki (JP); **Jun Akabane**, Yokohama (JP); **Masuhiro Yamasaki**, Tokyo (JP)

(73) Assignee: **Nikon Corporation**, Tokyo (JP)

(**) Term: **15 Years**

(21) Appl. No.: **29/821,568**

(22) Filed: **Dec. 30, 2021**

Related U.S. Application Data

(62) Division of application No. 29/707,130, filed on Sep. 26, 2019, now Pat. No. Des. 942,372.

(57) **CLAIM**

The ornamental design for a battery, as shown and described.

DESCRIPTION

FIG. 1 is a front, top, and left side perspective view of a battery showing our new design;

FIG. 2 is a front view thereof;

FIG. 3 is a rear view thereof;

FIG. 4 is a top plan view thereof;

FIG. 5 is a right side view thereof; and,

FIG. 6 is a left side view thereof.

The dash-dash broken lines illustrate portions of the battery that form no part of the claimed design. The dot-dash broken lines illustrate the boundary of the claim and form no part of the claimed design.

1 Claim, 6 Drawing Sheets
